UNITED STATES PATENT OFFICE.

EDWARD M. JOHN AND FRANK P. MOINETT, OF CANTON, OHIO.

SHOE-SHINING DEVICE.

Application filed March 17, 1924. Serial No. 699,902.

To all whom it may concern:

Be it known that we, EDWARD M. JOHN and FRANK P. MOINETT, citizens of the United States, residing at Canton, in the 5 county of Stark and State of Ohio, have invented certain new and useful Improvements in Shoe-Shining Devices, of which the following is a specification.

The present invention relates to a shoe 10 shining device and has for its principal object to provide a device of this nature which may be utilized in reciprocating a brush or rotating a brush.

An important object of the invention is 15 to provide a simple and efficient construction which is compact, comparatively inexpensive to manufacture, durable, strong, and well adapted to the purpose for which it is designed.

With the above and numerous other objects in view as will appear as the description progresses, the invention resides in certain novel features of construction, and in the combination and arrangement of parts 25 as will be hereinafter more fully described and claimed.

In the drawing:

Figure 1 is a longitudinal section taken through the device embodying our invention,

Figure 2 is a fragmentary longitudinal section illustrating a central portion of the device, said section being taken substantially at right angles to that shown in Figure 1, and

Figures 3 and 4 are elevations of the brushes used with the device.

Referring to the drawing in detail it will be seen that the body A is provided with an intermediately disposed slot 5 terminating at one end in a cylindrical bore 6 and at its other end in a cylindrical bore 7. The bore 6 is substantially larger than the bore 7. A shaft 8 extends transversely through the body A and intermediately through the slot 5. A cam 9 is keyed to this shaft 8 and rotatable in the slot 5. A housing 10 is built about the intermediate portion of the body A and is provided with an opening 11 so that a flexible shaft may be inserted therethrough into engagement with an end of the shaft 8 for rotation thereof and operation of the cam 9. A rod 12 is constructed at one end with an enlargement or head 13 from which extends the projection 14 disposed in the slot 5 to be engaged by the cam

9. A bushing 16 is mounted in the end of the bore 6 so that the rod 12 may reciprocate therethrough. A spring 17 of the helical type is disposed about the rod 12 and impinges against the bushing 16 and one end of the head or enlargement 13 so as to normally hold the head or enlargement 13 in abutment with the shoulder or end 17 of the bore 6. The exterior end of the rod 12 is bifurcated so as to provide a slot 19 having notches 20 therein so that either of the brushes shown in Figures 3 and 4 may be engaged therewith. These brushes are provided with sleeves 21 having pins 22 extending transversely thereof. These sleeves may be positioned over the exposed end of the rod 12 and the pins passing into the slot 19 will be engaged in the notches 20. The brush B shown in Figure 3 is of the rotary type while the brush C shown in Figure 4 is of the reciprocatory type.

Upon rotation of the shaft 8 when connected with the usual flexible shafting such as is in common use, the cam 9 will be actuated so as to reciprocate the rod 12; that is, the cam will move it to the left in Figure 1 and the spring 17 will move it to the right thereby reciprocating brush C when attached as previously indicated.

A shaft 23 extends into the bore 7 and is attached to the body by means of a pin 24 or in any other suitable manner. A handle in the form of a sleeve 25 is disposed over the shaft so that the shaft may be rotated therein, being mounted by means of ball bearings 26 and 27. The ball bearings 26 and 27 and the handle 25 are held in proper relation to each other on the shaft 23 by means of a nut 29 threaded on the shaft so as to bear against the ball bearings 26 and 27 in engagement with the body A. The end 30 of the shaft 23 which extends beyond the nut 29 is adapted to be engaged with a flexible shaft so that the shaft 23 may be rotated thereby rotating the body A and the rod 12, it being noted that the rod 12 will rotate with the body because of the projection 14 fitting in the slot 5.

When the reciprocating brush B is to be used it is of course desirable that the handle 25 be keyed to the shaft 23 and in order to accomplish this said shaft 23 is provided with an opening 31 and the sleeve is provided with a pin 32 slidably therethrough for engagement with the opening 31. This

pin 32 is provided with a head 33 from which extends a projection 34 which when engaged with the exterior of the handle 25 holds the pin 32 out of engagement with the shaft 23 and its opening 31 as is shown to advantage in Figure 1. The handle, however, is provided with an opening 35 for receiving this pin 34 in order that the pin 32 may penetrate into the opening 31 as is shown to advantage in Figure 2 thereby fixing the handle to the shaft 23.

It is thought that the construction and operation of this device should now be clearly understood without any more detailed description. It is desired, however, to point out that numerous changes in the details of construction, and in the combination and arrangement of parts may be resorted to without departing from the spirit or scope of the invention as hereinafter claimed or sacrificing any of its advantages.

Having thus described our invention what we claim as new is:

1. A brushing apparatus of the class described including a body, a reciprocatory rod mounted in the body, a shaft extended transversely of the body, a cam on said shaft engageable with said rod for moving the same, a spring associated with the rod for holding the same in engagement with the cam, a handle including a supporting shaft secured to said body, a hand grip rotatably mounted on the supporting shaft and means for selectively keying the grip immovably on said supporting shaft.

2. A brushing apparatus of the class described including a body provided with an intermediately disposed slot, a bore at one end of the slot, a second bore at the other end of the slot, a shaft extended through the intermediate portion of the body and through the slot provided therein, and a cam fixed to the shaft for movement in the slot, a rod mounted to reciprocate within the first bore, a projection extended from the rod to the slot, a spring associated with the rod to hold the projection in abutment with the cam whereby upon rotation of the cam the rod will be reciprocated, a handle including a supporting shaft having one end situated in the second bore and fixed to the

body, a hand grip rotatably mounted on the supporting shaft, said supporting shaft and said hand grip provided with registerable openings, and a pin insertable through the openings for selectively keying the grip immovably to said supporting shaft.

3. A brushing apparatus of the class described including a body, a reciprocatory rod mounted in the body, a shaft extended transversely of the body, a cam on said shaft engageable with said rod for moving the same, a spring associated with the rod for holding the same in engagement with the cam, a handle including a supporting shaft secured to said body, a hand grip rotatably mounted on the supporting shaft, said hand grip and said shaft provided with registerable openings, and a pin insertable through said openings for selectively keying the grip immovably to said supporting shaft.

4. A brushing apparatus of the class described including a body, a reciprocatory rod mounted in the body, a shaft extended transversely of the body, a cam on said shaft engageable with said rod for moving the same, a spring associated with the rod for holding the same in engagement with the cam, a handle including a supporting shaft secured to said body, a hand grip rotatably mounted on the supporting shaft, said supporting shaft and said hand grip provided with registerable openings, a pin insertable into said openings for selectively keying the grip immovably to said supporting shaft, a head provided on the end of the pin, a second pin provided on the head, and said handle grip provided with a second opening for receiving the second pin whereby when said second pin is in the second opening the first pin is insertable through the opening of the supporting shaft and when not in said second opening the first pin is not in the opening of the supporting shaft.

In testimony whereof we affix our signatures in presence of two witnesses.

EDWARD M. JOHN.
FRANK P. MOINETT.
